UNITED STATES PATENT OFFICE

2,170,481

SUBMARINE BARRIER

James J. Morrison and James F. Howe, Worcester, Mass., assignors to The American Steel and Wire Company of New Jersey, a corporation of New Jersey

Application August 12, 1936, Serial No. 95,651

4 Claims. (Cl. 114—240)

This invention relates to submarine barriers, and, more particularly, to barriers adapted for use with a signal system, whereby moving under-water bodies, such as submarines, coming in contact therewith, will actuate the signal mechanism to reveal their presence.

The present invention relates to nets of a sturdy but light construction, which may be manufactured in simple elemental parts on shore and readily assembled at the location wherein use is desired. Their construction is such that any number of the elemental parts may be joined together to cover areas beneath the surface of a body of water of any desired vertical and lateral extent. Each net, when assembled, is adapted to function not so much as a defensive barrier for effectually excluding submarine craft, but rather as an element in a signal system which will, when contacted by such craft, cause surface signals to be actuated revealing the presence and exact location of the submarine.

Other objects and advantages will become apparent as the description proceeds, in which:

Figure 1 is an elevational view of one embodiment of the present invention illustrated in installed position.

Figure 2 is an enlarged fragmentary elevational view of the device illustrated in Figure 1.

Figure 3 is an enlarged detailed view of a fastening employed in the present invention.

Figure 4 is a sectional view taken along line IV—IV of Figure 3.

Figure 5 is a composite elevation and sectional view of a form of fastening similar to that shown in Figures 3 and 4.

Figure 6 is a sectional view taken along line VI—VI in Figure 2.

Figure 7 is a fragmentary detailed view of the device illustrated in Figure 6.

Figure 8 is an enlarged detailed view of one form of frangible link embodied in the construction of the present invention.

Figure 9 is a partial sectional view taken along line IX—IX of Figure 8.

Figure 10 is an elevational view of still another embodiment of the present invention shown in installed position.

Figure 11 is an enlarged fragmentary elevational view of the construction shown in Figure 10.

Figures 12, 13, 14 and 15 are detailed views of modified forms of fastening devices which are employed in the various embodiments of our invention.

In the drawings, the embodiment of the inven-

tion illustrated in Figures 1 and 2 comprises a retiform body composed of vertical strands 1 and horizontal strands 2, secured at their points of intersection by fastenings 3. Suitable types of fastenings for this purpose are illustrated in Figures 3, 4 and 5, which will be described in greater detail hereinafter. The retiform body thus formed, is adapted to be suspended between the surface of a body of water and its bottom, and to this end a suspension cable 4 is provided, having floats or buoys 5 arranged at suitable spaced intervals along its length. The opposite extremities of the supporting cable 4 may be anchored at fixed points by suitable anchorages disposed either in the water, or upon adjacent embankments of the land. It may be retained under tension so as to reduce the catenary thereof, which function will be further augmented by the floats or buoys 5. The buoys alone may be relied upon to perform this function.

Certain of the buoys 5, are provided with anchor cables 6, which extend down through the depth of the water to suitable anchoring means 7, upon the bottom. The retiform body is hung from the supported cable 4 by suitable clamping members 8, which are provided with vertical cable sockets 9 that are adapted to receive the upper extremities of the vertical cable members 1.

At intervals along the length of certain of the vertical and horizontal strands 1 and 2, are interposed frangible link members 10, of any suitable form, a preferential construction of which is shown in Figures 8 and 9. These links are adapted to join adjacent sections that comprise each vertical and horizontal strand, and are composed of rope sockets 11 and 12, which are fixed to the adjacent ends of the several strand sections. These sockets are provided with clevises 13 and clevis pins 14, arranged to receive a frangible or deformable link member 15. Each of the link members is preferably arranged with its opposite ends bent over in opposite directions about the clevis pins 14, in a substantial S shape as is shown in Figure 9. The nature of these links is such that when pressure is applied to the portions of the netting subtended thereby, the link portions 15, will either rupture or deform so as to permit the adjacent strand sections secured thereby, to part, whereby the net portion usually supported by these links, is completely severed from the body portion of the net.

An electrical conductor 16 is attached, preferably in a serpentine manner, to the vertical and horizontal strands of the net by suitable fasten-

ings 17. The fastenings 3, which are employed to secure the vertical and horizontal strands together at their intersections, are usually of the form disclosed in Figure 5; that is, two complementary annular members 18 and 19, joined by rivets 20 to secure the intersecting strands together, as shown. However, at the intersections where the electrical conductor 16 is laid, one of the annular members is constructed so as to provide a spool 21, which is adapted to receive several turns of the conductor 16, as is shown in Figures 3 and 4. The conductor, when fastened in this manner, is firmly secured against axial movement relative to the strands along which it is laid.

The conductor 16 is accommodated, at the frangible links 10, by spool members 22, which are secured upon the clevis pins 14, in such a manner as to provide for several turns of the conductor being taken about each spool, and so as to obtain a single diameter of the conductor bridging the space between the spools, substantially parallel and adjacent to the link 15. This arrangement is adopted to insure that the portion of the conductor extending between each of the link spools 22 will be ruptured, in the eventuality of the associated link giving way, for purposes to be presently explained. In this manner, the electrical conductor is laid across the entire net, including the portions thereof retained by the frangible links, so as to cover substantially the entire planar area defined thereby.

A main power cable 23, is carried along the netting adjacent the support cable 4, by suitable brackets 24, which form a part of the clamp members 8. This main power cable connects the portions of the electrical conductor 16 that span the frangible portions of the net to a system of relays, which are arranged to actuate signals of any desired character. In a preferred embodiment, the signals and relays may be located within certain of the buoys, as is indicated at 25, which are instrumental in supporting the net-support cable 4. Suitable connections between the relays (not shown), signalling means, conductor 16, and power cable 23, are shown at 26. The power cable may extend to as many of the net sections as are employed in the system, and may be extended at one end of the net to a suitable station 28, on shore, as by a submarine cable 27, or in any other suitable manner. Net sections may be added indefinitely to increase the lateral or vertical extent of the net by simply annexing additional sections to those already in place by means of strand clamps 34. As the net is enlarged in lateral extent, the newly added sections may be electrified for signal purposes by splicing additional lengths onto the power cable 23, and conductor 16.

60 The wiring system is such that when a frangible portion of the netting is engaged by a submarine craft, it will be severed from the body of the netting, and the portions of the conductor 16, bridging the frangible links, will be broken and carried away with the severed portions of the net. Upon being broken, one of the relays (not shown) is actuated to cause an adjacent signal 25 to indicate at the surface of the water, or in a remote station, such as at 28, which frangible section of netting has been carried away, thus revealing the location of the submarine body.

In the embodiment illustrated in Figure 10, we have provided a netting similar to that already described but which is perhaps better adapted for 75 protection of bodies of water of considerable

depth. The construction is quite similar to that hereinbefore described, in that it employs buoys 5, supporting cable 4, anchor strands 6, anchors 7, hanger-clamps 8, frangible links 10, and strand-intersection fasteners 3. It differs from the preceding structure only in that each section, instead of being applied to adjacent sections by strand clamps 34, so as to form extensions of the netting strands already in place as coaxial continuations thereof, is formed in the manner of individual curtains, which may be dropped or unfurled in overlapping relationship to the adjacent sections from the support cable 4. In this construction, it may be desirable to provide each buoy 5 with a pair of anchor strands 6, to which the overlapping adjacent sections are secured at points where the elemental strands 2 of the latter intersect the vertically disposed anchoring cable 6. A clamp 33, suitable for this purpose, is clearly illustrated in Figure 14.

20 In this embodiment of the present invention, it is only necessary to provide frangible links 10 in each of the vertical strands 1, adjacent the upper extremities thereof, which links are bridged by portions of the conductor 16, in a manner similar to that already described. The frangible links 10 are designed to permit easy breakage under strain, as has already been explained, so that the vertical curtain formed by each net section will be torn out when contacted by a submarine craft. The nature of the fastenings 33, shown in Figure 14, by means of which the adjacent overlapping sections of netting are made fast to the anchor ropes 6, is such that will permit of the curtain sections also being pulled free of the anchor cables, when the frangible links 10 are caused to fail upon the application of strain.

25 In all embodiments, the disposition and extent of the conductor 16, is such as will assure its being severed somewhere along its length either upon any of the frangible net sections being carried away, or upon the application of cutting devices to remove any portions of the netting by stealth.

If it is desired to provide a strong, impregnable defense netting, the frangible links may be omitted from the above construction, and instead of the annular fastening device 3 being employed to secure the various vertical and horizontal strands together at their intersection, a sturdy cable clamp 29 may be employed, similar to that shown in Figures 12 and 13. In this form of net, the electrical conductor 16, the main power cable 23, and associated relay signal circuits, are retained to function in manner similar to that which has already been described, in the event that the netting is cut by a submarine craft seeking to penetrate the protected area. Such a net is adapted to withstand considerable force so as to effectually resist the passage of submarine craft, and is only susceptible of penetration when sheared or cut under water by the aggressor vessel. Such attempts to penetrate the netting will be indicated by surface signals both adjacent and remote from the net.

30 If it is desired to provide a defense net of the curtain type that will effectually prevent the passage of submarine craft, the frangible or deformable fastening shown in Figure 14, for securing the overlapping edges of adjacent sections to the anchor cable 6, may be replaced by a form of fastening shown in Figure 15, which is comprised of a sturdy clevis 30 with associated pin 31, and which will resist breaking strains and retain the elements of the net securely together.

In the frangible link type of net disclosed first hereinabove, it will be observed that its value lies not so much as constituting a defensive barrier, as in constituting a signalling means whereby hostile submarine craft may be instantly detected, located, and destroyed or captured. Its only utility as a defensive structure lies in the fact that any one of its frangible portions, after being disassociated from the body of the net, will

10 be inclined to envelop the craft within its mesh and thereby will be most likely to become fouled in its propellers and steering gear. In this manner, the net does serve to disable hostile vessels, while at the same time, reveals the presence and 15 location thereof. The latter type of net; namely, the impregnable defensive barrier type, is arranged to effectually exclude hostile craft from penetrating into a restricted zone. It is adapted 20 only to reveal their presence and location in the event an attempt is made to cut through them, in which case the alarm as to the presence and location of the offensive submarine craft is given.

Nets embodying the present invention are easily and rapidly installed in place and are made to 25 any desired size by simply adding additional sections to those already in place. In the case of sections being damaged or removed by the penetration of a submarine craft, replacements may be kept on hand and rapidly installed to 30 repair the breach. The fittings; as, the hanger clamps 8, fastenings 3, 30 and 33, have been carefully designed with a thought toward facilitating such replacements.

While we have shown and described specific 35 embodiments of the present invention, it is to be understood that we do not wish to be limited exactly thereto, since various modifications may be made without departing from the scope of the invention as defined by the following claims.

40 We claim:

1. In an electric signalling system including an electric signal, a submarine barrier comprising a mesh-like barrier member disposed to obstruct a sub-surface water-way, at least one electric 45 conductor element carried on said mesh-like barrier and operably connected with said electric signal, spaced points of said mesh-like barrier being weakened so as to separate when stressed, and said electric conductor bridging said spaced 50 points of said barrier and arranged to break when

said mesh separates at said weakened points and to operate said electric signal.

2. A device for indicating the presence of sub-surface water craft comprising, in combination, a mesh-like barrier member disposed to obstruct a sub-surface water-way, means for supporting and anchoring said mesh-like barrier in position, a main power conductor carried by said supporting means, a signaling system connected to said conductor, and an electric conductor carried by portions of said mesh-like barrier member and connected to said main power conductor, spaced points of said mesh-like barrier being weakened so as to separate when stressed, said electric conductor bridging said weakened portions of said mesh-like barrier to break when said mesh-like barrier separates at said weakened portions and operate said signaling system.

3. In a signalling system including an electric signal, a submarine barrier comprising crossed strands forming a mesh-like barrier member disposed to obstruct a subsurface water-way, an electrical conductor carried by certain of said strands and operably connected to an electric signal system, frangible link members interposed between certain of said strands at spaced points in said mesh-like barrier, and means on at least some of said frangible links for supporting the electrical conductor across said links so that when said mesh-like barrier is ruptured at the frangible link supporting said electrical conductor, said electrical conductor will break to operate said signal.

4. In a signalling system including an electric signal, a submarine net comprising, in combination, a plurality of sections, a surface cable adapted to support the top edge of said net, anchoring means for said net, electrical conductors carried by portions of said net and operably connected with the electric signal, frangible fastenings connecting spaced portions of said net and means on at least some of said frangible fastenings for bridging said electrical conductors across the frangible fastenings and for holding the same against substantial axial movement so that when said frangible fastenings are broken when stressed, said electrical conductors will break to operate said signal.

JAMES J. MORRISON.
